SEWING MACHINE FOR COLLARS

Harry Johnston, St. Louis, Mo., assignor, by direct and mesne assignments, of one-half to Edward Greensfelder and Mercantile-Commerce Bank and Trust Company, trustees under the will of Wilton Rubinstein, deceased, and one-half to Edward Greensfelder and Mercantile-Commerce Bank and Trust Company, trustees for Blanche Rubinstein, Louise Rubinstein, Ann Rubinstein, and Peggy Rubinstein

Application June 3, 1939, Serial No. 277,310

1 Claim. (Cl. 112—136)

This invention relates to sewing machines for collars; and has special reference to sewing machines for attaching to the infold ply of an apparel collar a tape extending longitudinally along the fold line and cooperating with adjacent attached collar elements to control and form a definite longitudinal fold line in the collar.

The present invention comprises improved devices for embodiment in sewing machines used for making apparel collars of the type disclosed in Wilton Rubinstein Patents Nos. 2,152,093 and 2,152,094, both dated March 28, 1939, as well as turned down collars of other types having means for controlling the fold lines along the line defining the union of the bands and capes and between upper edges of separate lining sections in the band and cape portions of the collars.

Objects of the invention are to provide an improvement in sewing machines for use in manufacturing collars of the turned down type which include unitary exposed and infold plies, respectively, extending the full length and width of the collar band and cape, comprising mechanism for attaching by parallel rows of stitches to the inner or concealed side of the infold ply of the collar an initially straight tape or strip that is curved and attached to the inner or concealed side of the infold ply across the fold line of the collar and extending a short distance downwardly into the cape and a short distance downwardly into the band without wrinkling either the tape or the collar ply; to provide means cooperating with a previously attached band lining section to guide the infold ply in a relationship in which the tape or strip covers and extends across the curved upper longitudinal edge of a band lining section that had been previously attached to the infold ply so that, as the parallel rows of stitches are formed to attach the tape or strip to the infold ply and to the cape lining section of the collar, said tape or strip will be curved in conformity with the upper curved edge of the band lining section and attached to the infold ply by curved lines of stitches without wrinkling any of the attached parts; and to provide mechanisms for greatly facilitating and expediting the manufacture of collars of the type disclosed in said patents.

Another object of the invention is to provide improved means for use in assuring the formation of parallel curved lines of stitches for attaching an originally straight tape or strip of pliable material to a flat collar ply along a curved line and across the curved edge of a collar lining section by curving said strip along said line and

edge and attaching the same to the collar ply without visibly distorting either the strip or the collar ply, or forming noticeable wrinkles or creases.

5 Various other objects and advantages of the invention will be apparent from the following description, reference being made to the annexed drawings, in which—

Fig. 1 is a front elevation of a part of a sewing machine for curving and attaching an originally straight strip or tape to a collar ply directly.

Fig. 2 is a plan view of a part of the machine looking in the direction indicated by the arrows at the ends of the line 2—2 of Fig. 1.

15 Fig. 3 is a left-hand side elevation of the mechanism shown in Fig. 1.

Fig. 4 is an enlarged sectional view approximately on the line 4—4 of Fig. 2.

Fig. 5 is a reduced plan view showing the position of the infold collar ply with one curved edge thereof functioning to position the collar ply during its passage through the machine while the tape is being attached to the concealed side thereof.

20 Fig. 6 is a perspective view of a part of the device shown in Fig. 2 cooperatively related to the feed dog of the sewing machine.

Fig. 7 is a plan view of the exposed side of the infold ply showing the longitudinal curved lines 30 of stitches attaching the strip or tape to the concealed side thereof.

Fig. 8 is a similar plan view of the concealed side of the collar ply showing the tape curved and attached by curved lines of stitches to the 35 collar ply.

Fig. 9 is a view showing the initial position of the collar ply contacting with a positioning device therefor before the stitches enter the collar ply to attach the tape thereto.

40 Fig. 10 is an enlarged plan view of an embodiment of the invention cooperating with the curved upper edge of an attached band lining section to guide the infold ply in a curved line through the sewing machine.

45 Fig. 11 is a side elevation of the mechanism shown in Fig. 10, illustrating more clearly the guides for the collar ply and the tape, respectively.

Fig. 12 is a front elevation of the devices shown 50 in Figs. 10 and 11.

This is a continuation in part of my abandoned application Serial No. 284,544, filed October 12, 1938, for improvements in sewing machines for collars.

55 In that specific part of the present invention

that is disclosed in said original application, a tape is attached to the concealed side of the infold ply of an apparel collar by means cooperating with the stitch-forming mechanism of a sewing machine for guiding the collar ply and the tape in a cooperative relationship in which the tape is attached to the concealed side of the collar ply by parallel curved lines of stitches. For convenience, this part of the invention is shown embodied in a sewing machine comprising a bed 1 supporting the present invention and the related mechanism of the sewing machine including the feed dog parts 2 and 3 separated by a space 4. A throat plate 5 is attached to the bed 1 and has an opening in which the feed dog parts 2 and 3 operate, and is provided with holes 6 and 7 through which the needles 8 and 9 operate to engage the needle threads 10 and 11 with the usual bobbin threads to form parallel lines of stitches through the materials being sewed. The needles 8 and 9 are attached to a supporting head 12 mounted on the vertically reciprocating needle bar 13. The presser foot 14 is attached to a vertically movable bar 15.

According to this specific form of the invention, a supporting bar or piece 16 is attached to a stationary part of the throat plate 5 between the needles 8 and 9 and in the space 4 approximately midway between the sides of the feed dog and extends relatively a considerable distance above the upper surface of the plate 5 and above the highest position of the feed dog (Fig. 4). During operation of the sewing machine, the parts are operated relatively to relieve pressure by the feed dog against the material—in this instance the tape 17—under the presser foot, thereby disengaging the feed dog from the material or tape which remains upon the stationary part 16, thereby permitting lateral turning of the material so that the tape may be curved and attached to the infold ply by curved parallel lines of stitches without wrinkling or buckling either the tape or the ply to which it is attached.

In this form of the invention, the straight unfolded tape is guided above the feed dog and the bar 16 by a guide 18 attached to the bed 1 forwardly beyond said feed dog, so that said tape is fed to proper position for engagement by the feed dog and the presser foot 14 and for operation of the needles 8 and 9 to form parallel lines of stitches through the margins of the tape.

The infold collar ply 19 has a curved edge 20 which contacts with the gages of the present invention to guide the collar ply properly for attachment of the tape 17 to said ply. A gage 21 having its gaging edge 22 toward the sewing mechanism is seated on the plate 5 and formed with a plainly visible portion 23 which may be a notch, groove, rib or other marker for use in locating the proper position of the end of the collar infold ply 19 preparatory for beginning sewing said infold ply and the tape 17 together. The gage 21 is secured to the plate 5 by a screw 24 passing through a slot 25 in said gage and into the plate 5. This permits the gage 21 to be turned to different positions about the screw 24 as an axis and to be adjusted in different positions toward and from the sewing mechanism. In its preparatory adjustment, the infold ply 19 is laid upon the bed 1 across the tape 17 with its curved outer end of the edge 20 against and matching the gaging edge 22 of the gage 21 and the extreme end of the band portion of the infold ply at the marker 23. Operation of the sewing machine is then started and the infold ply of the

collar is moved along with the tape 17, and two rows of stitches 26 and 27 are formed. Movement of the infold ply 19 is continued in a substantially straight direction, the end portion of said ply rising above and moving across the inner end of the gage 21 until the curved edge 20 of said infold ply contacts with a gage 28 having a slot 29 through which the screw 24 passes to secure said gage 28 in its proper position. The slot 29 permits the gage 28 to be turned or to be moved longitudinally to different adjusted positions with the gage 21 or with respect thereto. When the curved edge 20 of the infold collar ply contacts with the gage 28, said collar ply is guided thereby, the tape 17 operating along the bar 16 which detaches said tape from positive restraint by the feed dog and the presser foot 14 when the feed dog moves downwardly in its usual operations. Such detachment of the tape 17 from the feed dog permits that necessary slight turning or pivotal movement of the infold ply 19 to maintain the curved edge 20 thereof constantly against the gage 28. This results in curving the tape 17 in conformity with the curved edge 20 of the collar ply 19 and attaching said tape to the collar ply by the two curved parallel rows of stitches 26 and 27 without visibly stretching any portion of the tape or collar ply or forming any visible wrinkles or folds. The gage 28 is attached to the bed 1 a substantial distance laterally beyond the feed dog 2-3. It engages the curved side edge 20 of the collar ply 19 during movement of the collar ply with the tape superimposed thereon. This causes the collar ply to move somewhat along a curved line of movement and to curve the tape along or relative to the ply. It also causes the needles to form curved parallel lines of stitches attaching the tape and the ply together throughout the entire distance that the collar ply is moved by the feed dog while the curved side edge of the ply is in engagement with the gage 28. This makes the individual stitches 26 of very slightly greater length than the corresponding individual stitches 27 because the needles 8 and 9 operate simultaneously and the line of stitches 26 are formed on a slightly greater radius of curvature than the line of stitches 27. After each collar ply 19 passes beyond the sewing mechanism, rows of stitches will continue to be formed along a short stretch of the tape 17 until another collar ply 19 is placed in position.

Wilton Rubinstein Patent No. 2,152,095, March 28, 1939, discloses an apparel collar in which the parts are assembled in a different cooperative relationship from the relationship of said parts disclosed in said Patents Nos. 2,152,093 and 2,152,094. According to said Patent No. 2,152,095, the turned down collar comprises an infold ply extending the full length and width of the collar and attached to the cooperating parts in a manner to form a fold line along which the band and cape may be turned against each other. The band includes a lining section attached to the concealed side thereof and having a curved upper edge separated by a longitudinal space from the complementarily curved upper edge of the cape lining section along the fold line of the collar. The tape extends longitudinally along said space and has one margin slightly overlapping and covering the curved upper marginal portion of the cape lining section and attached thereto by a longitudinal curved line of stitches parallel with a curved line of stitches attaching the upper margin of the band lining section directly to the infold ply, and also parallel with another curved

line of stitches attaching the opposite margin of the tape directly to the cape portion of the infold ply beyond said fold line space. In making collars having the tape overlapping and attached to the upper margin of the band lining section and to the infold ply by one curved line of stitches and attached to the infold ply beyond the fold line space, it is important that the two curved lines of stitches attaching the tape in this manner parallel the previously formed curved line of stitches attaching the band lining section to the infold ply, and also parallel the upper edge of the band lining section.

Mechanism for holding and guiding the infold ply of the collar and the attached band lining section, and for placing the tape thereon in proper relationship during attachment of the tape to said infold ply and band lining section by parallel curved lines of stitches, is illustrated in Figs. 10, 11 and 12 of the drawings, in which reference numerals with exponents are analogous to the parts designated by the same reference numerals without exponents in the preceding views of the drawings.

In this device, a bracket or frame 30 has one end rigidly attached to the vertical presser foot bar 15' by a removable and replaceable fastener 31. An arm 32 is also attached to the bar 15' by the fastener 31. An arm 33 in connection with the front end of the bracket 30 extends laterally beyond and forwardly from the needles 8' and 9', the entire bracket structure being relatively a considerable distance above the bed plate 1' so that it will not interfere with the operation of the stitch-forming mechanism or with inspection of the work at the stitch-forming mechanism by the operative. A resilient member comprising a downwardly extended part 34 and a rearwardly extended part 35 in connection with the part 34 is attached to the arm 33 by removable and replaceable fasteners 36.

The collar disclosed in said Wilton Rubinstein Patent No. 2,152,095 has a band lining section 37 (designated 3 in said patent), formed with a curved upper edge 38, attached directly to the concealed side of the infold ply 19' by a longitudinal curved line of stitches 39 parallel with the edge 38.

The present invention also comprises a presser foot 40 attached to the lower end of the arm 32 by a pin 41 and having its forwardly extended portion provided with holes 42 through which the needles 8' and 9' operate. The front end of the presser foot 40 is formed with an upwardly and forwardly inclined extension 43 having a wide slot 44 therein. In this instance, it is essential that the width of the slot 44 be greater than the distance between the points of the needles 8' and 9'. The tape 17' is fed through the slot 44 and guided thereby below the presser foot 40 to the stitch-forming mechanism. The tape 17' is guided in such a manner that the margins thereof extend beyond the needles 8' and 9' so that the parallel curved lines of stitches 26' and 27' pass through said tape and the collar ply 19'.

The rearwardly extended resilient part 35 is substantially above the work or materials being sewed, and does not interfere with the placement thereof at the stitch-forming mechanism, nor

with the subsequent movement thereof during operation of the stitch-forming mechanism. The part 35 is formed with a downwardly extended flange 45 which engages the curved upper edge 38 of the band lining section 37 during placement of the work, and during subsequent operations in which the curved parallel lines of stitches 26' and 27' are formed. Because of the fact that the curved line of stitches 26' must be formed beyond the curved edge 38 of the band lining section, a distance at least equaling the width of the longitudinal fold line of the collar, it is essential that the flange 45 be in a vertical plane between the needles 8' and 9'. It is also important that the parts 35 and 45 be forwardly beyond the needles 8' and 9' far enough not to prevent the tape 17' from lying perfectly flat upon the subjacent band lining section 37 and collar ply 19', and the parts are as shown.

During movement of the collar ply and attached band lining section to and through the stitch-forming mechanism, the part 45, by engagement with the curved side edge 38 of the band lining section 37, prevents relative displacement of any of the parts to be attached and assures that the two parallel curved lines of stitches 26' and 27' will be formed parallel with the edges 38 and pre-formed line of stitches 39.

This device very greatly expedites and facilitates attachment of the tape 17' to the concealed side of the infold ply of the collar in a manner by which, when the collar is completed, a controlled and definite longitudinal fold line is provided between the line of stitches 26' and the upper edge 38 of the band lining section. For the attainment of this desirable effect, the parts must be secured together with such accuracy and precision as could not be easily and practicably attained heretofore by available sewing machines or devices therefor.

It should now be apparent that the present invention provides a solution of the difficulties inherent in the attachment of a straight tape to a flat piece of material along a radius of curvature by parallel curved lines of simultaneously formed stitches without buckling or wrinkling or otherwise visibly distorting any of the parts included in the work. The devices may be modified and varied otherwise than as specifically disclosed without departure from the nature and principle of the invention.

I claim:

In a sewing machine having a supporting bed, a feed dog, a throat plate through which the feed dog operates, and two needles for forming two parallel lines of stitches simultaneously; a device for guiding a straight tape over the entire upper side of the feed dog, an element located between said needles and extending above said throat plate and above said feed dog for disengaging the tape from the feed dog after each operation of the needles, and a gage for engaging a curved side edge of a collar ply during movement thereof with the tape whereby said tape will be curved and curved lines of stitches will be formed by said needles approximately parallel with the said curved edge of said collar ply.

HARRY JOHNSTON.
